CLAIM

The ornamental design for an egg carton as shown and described.

DESCRIPTION

FIG. 1 is a front perspective view of an egg carton showing the new design in a closed configuration;

FIG. 2 is a rear perspective view thereof;

FIG. 3 is a bottom perspective view thereof;

FIG. 4 is a top plan view thereof;

FIG. 5 is a left side elevation view thereof (the right side elevation view is a mirror image of FIG. 5);

FIG. 6 is a rear elevation view thereof;

FIG. 7 is a front elevation view thereof;

FIG. 8 is a bottom plan view thereof;

FIG. 9 is a top perspective view thereof showing the egg carton in an open configuration;

FIG. 10 is a bottom perspective view thereof;

FIG. 11 is a top plan view thereof; and,

FIG. 12 is a left side elevation view thereof (the right side elevation view is a mirror image of FIG. 12).

The short dash-short dash type broken lines shown in the drawing views are included for the purpose of showing environmental subject matter that forms no part of the claimed design. The long dash-short dash type broken lines shown in the drawing views define the unclaimed boundaries of the claimed design.
